UNITED STATES PATENT OFFICE.

FREDERICK G. SARGENT, OF GRANITEVILLE, MASSACHUSETTS.

IMPROVEMENT IN ROLLS FOR WOOL-WASHING MACHINES.

Specification forming part of Letters Patent No. 222,423, dated December 9, 1879; application filed January 24, 1879.

To all whom it may concern:

Be it known that I, FREDERICK G. SARGENT, of Graniteville, in the county of Middlesex and State of Massachusetts, have invented a new and useful Improvement in Rolls of Wool-Washing Machines, of which the following is a specification.

My improvement relates to the use of a roller or of rolls made of cork, in the manner hereinafter described, for use in wool-washing machines, which are intended to take the wool in the condition in which it comes from the animal and cleanse or scour it of its oil, gum, alkali, dirt, and other foreign substances.

Heretofore, in such machines, rolls constructed of various materials have been tried and used, but, owing to the presence, when it comes from the animal, of certain oily and alkaline substances not elsewhere found in fiber or fabric, none of the ordinary washing devices could be successfully applied to wool-washing; and, owing to the destructive effects of said substances when made soluble in the vats of the washing machine, none of the ordinary elastic squeezing-rolls could be made to operate for more than a very limited period of time.

As it was not possible to properly squeeze the fluid from an irregular sheet of wool with metal rollers, it has long been a problem for the inventor to find some material which would take the place of the perishable wool-wound metal roll or the rubber-faced roll, one of which lacked strength in its material, and the other of which lost its strength and elasticity by the destructive action of this peculiar scouring-liquid coming from the wool.

It has been found that until a certain amount of the oily, gummy, and alkaline substances are obtained in solution in the scouring-liquid by passing wool through the liquid first put in the machine, no satisfactory scouring of wool could be done, and that afterward the longer the scouring-liquid could be used the better the work done by it, owing to its increased strength.

It has been found that none of the elastic rolls could be successfully operated without being coupled to their companion rolls, either because of their tendency to flatten or slip at the point of pressure and contact with the companion roll, or to tear and strip one by the

other, and also that their hold upon the wool is less as it comes up saturated with this before-mentioned peculiar scouring-liquid, than it is after it has been squeezed, and that it therefore became necessary to use a doffer to prevent portions of the wool which adhered or felted to the roll going around and again passing between the rolls and accumulating larger quantities.

It therefore became desirable and necessary to obtain a roll which would resist the destructive effects of this peculiar alkaline, oily, and gummy scouring-liquid, while at the same time having the qualities of elasticity, quickness of hold in this peculiar liquid, and strength of material specially desirable in a roll designed to receive, under great pressure from this oily liquid, such a fiber as wool.

It was also desirable to obtain a material which would not felt small quantities of wool upon itself when used as a roll, and could be used with another roll without connecting the shafts of companion rolls by coupling-gears.

It is the object of my invention to provide such a roll for the special place, purpose, and condition above stated.

My invention consists in discovering that cork will resist the oil, alkali, and other destructive substances which are found in wool as it comes from the animal, and which become soluble in the scouring-liquid, and are a necessity to its perfect action, and that it possesses the property of nipping or catching the wool quickly as it comes saturated with the scouring-liquid, and loosening its hold upon it when pressed or squeezed comparatively dry by rolls constructed of it; and also forming it into a roller for wool washing or scouring machines, which has a cork face, and is built up with a shaft and metallic washers in such a manner as to prevent the cork from turning on its shaft, and without making one part of its surface less elastic than another, and since this cork roll must be subjected to the great pressure of from seven to nine tons, to likewise so construct it as to be able to successfully and continuously operate under it, with or without its shaft being coupled to that of its companion roll.

In the accompanying drawings, Figure 1 represents a roll constructed according to my

improvement. Fig. 2 represents an elevation of one of the washers, showing rib *f* on its inclined face.

A represents the shaft for the roller on which it revolves, provided with bearings at its ends. *B B* are collars made nearly the intended diameter of the roll, having a thread cut in them to engage with that cut on the shaft to compress and retain the annular layers of cork *c c*, forming the elastic face of the roll in position. *D D* are tapered washers having radial ribs *f* formed upon their inclined faces to obtain a greater hold upon the cork to prevent its rotating on the shaft. These washers I construct thicker at their inner edges than at their circumference, in order that they may have the necessary strength and may compress the cork more solidly near the shaft, and also to allow in parts of the roll adjacent to and over their edges the same radial elasticity as elsewhere in the roll, which would not be the case if the edges of the washers were thickened.

I construct the radial rib wedge-shaped, so that the above-mentioned action will be facilitated, and the cork between the washers will not be compressed in one part more than another, and the fiber torn as would be the case if the rib was of any other form. By thus obviating unequal pressure in building up the structure I produce a roll of homogeneous elasticity, so that no undue compression of the substance in one part more than in another on a right line with the shaft occurs when pressure is applied to the face of the roll, or while it is being built up, as would be the case if the washers or ribs were of other form.

The washer *D*, when viewed on a section made by a line cutting it into two equal semi-annular pieces, appears as two triangles with their shorter sides opposite separated by the diameter of the hole which existed in the washer. The wedge-shaped radial ribs are placed with their length radial to the center of the washer, and are wedge-shaped in cross-

section. I thus produce a roll which operates more equally and is more durable.

e is a key or spline put in a groove in the shaft to prevent the washers *D* from rotating upon the shaft. *s s* are layers of felt, which are inserted, if desired, between the washers and the cork, but they may be omitted.

In order to construct the rollers I cut the cork in annular sections having a hole the size of the shaft through the center. I then attach one of the collars *B* in place on the shaft and slip on one or more of the annular cork-sections *c*. At a suitable distance I put on a layer of felt, *s*. I then slip on one of the washers *D*, and laying upon it another layer of felt proceed to make up another portion of the roll by slipping on cork sections, as before, and another layer of felt and a washer, and so proceed until the entire length of the roll is completed, after which I screw up the collar at the end and bind the whole firmly together, by this means rendering it solid and preventing its turning on the shaft.

If desired, layers of felt may be omitted without departing from the spirit of my invention.

Instead of using a round shaft with a spline a shaft may be used square in cross-section where the cork and washers are slipped upon it.

What I claim as new and of my invention is—

1. A roll having a pressure-surface made of cork, in a wool washing or scouring machine, adapted to scour and cleanse the wool as it comes from the animal, substantially as described.

2. In combination with a metal shaft and washers, made thicker at their inner than their outer edge, cork annular rings forming a roll, substantially as described.
